UNITED STATES PATENT OFFICE.

CHARLES E. BENTLEY, OF NEW YORK, N. Y.

EMBROIDERY-SEAM.

SPECIFICATION forming part of Letters Patent No. 696,540, dated April 1, 1902.

Application filed August 7, 1901. Serial No. 71,165. (No model.)

To all whom it may concern:

Be it known that I, CHARLES E. BENTLEY, a citizen of the United States of America, residing at the borough of Manhattan, city of New York, State of New York, have invented 5 a new and useful Embroidery-Seam, of which the following is a specification.

This invention has for its object to provide a new and improved embroidery-seam designed 10 more especially as an open-work spangle-ornamented seam useful for uniting two pieces of lace or dress goods or other fabric.

The invention will first be described, and then will be particularly defined in claims 15 hereinafter set forth.

Reference is to be made to the accompanying drawings, forming part of this specification, and in which—

Figure 1 is a face or plan view of two pieces 20 of fabric united by the spangle-retaining threads of the seam. Fig. 2 is a cross-section taken on the line $x-x$ in Fig. 1; and Fig. 3 is a central longitudinal section of the seam-threads and spangles, taken on the line $y-y$ in 25 Fig. 1.

In the preferred open-work embroidery-seam I use two separated and substantially parallel pieces of fabric 1 2, two zigzag crossing upper or needle threads 3 4, two corresponding or aligned zigzag crossing under or 30 shuttle threads 5 6, and spangles 7 or other analogous pierced or hollow ornaments, which are sustained in planes between the two crossing upper threads and the two crossing under 35 threads and intermediately of the width of the seam or about midway between the two pieces of fabric.

In producing the illustrated open-work seam in the preferred manner the two crossing needle-threads 3 4 are passed in loops 8 9, respectively, through one piece of fabric, near its edge, (say the fabric 1,) where said loops are caught and interlocked by the corresponding shuttle-threads 5 6. Thence the four 45 threads 3 4 5 6 are passed diagonally to the row of spangles 7, which are suitably sustained in planes to allow the needle-threads 3 4 to pass over them and the shuttle-threads 5 6 to pass under them. The needle-threads 50 3 4 are then passed downward in loops 10 11 through the openings of the spangles, whereat said loops are interlocked by the two shuttle-

threads 5 6, and from these interlocked loops 10 11 the threads 3 4 5 6 continue their diagonal course across the seam to places a little 55 past the edge of the other piece of fabric 2, through which the needle-threads 3 4 are passed downward in loops 12 13, which are interlocked by the shuttle-threads 5 6. A reverse diagonal course is then given the four 60 threads, and the needle-threads 3 4 are again passed downward in loops 10 11 through the spangle-openings, where they are interlocked by the shuttle-threads 5 6, and thence the threads continue the same reverse diagonal 65 course back to the piece of fabric 1 and the needle-threads 3 4 are again passed in loops 8 9 through this piece of fabric, near its edge, and these loops are interlocked by the shuttle-threads 5 6, and so on continuously as the 70 threads are laid in zigzag course along the seam. With this relative arrangement of the needle-threads, the shuttle-threads, and the spangles it will be seen that the spangles are sustained flatwise and so that they cannot 75 turn upon edge and that they are very securely held in a substantially straight row at and along the center or intermediate portion of the seam and that the two pieces of fabric 1 2 are mutually connected and supported by 80 the interlocked zigzag spangle-supporting needle and shuttle threads of the seam.

The precise method or sequence of laying the zigzag threads to mutually support the fabric and the spangles or other ornaments is 85 immaterial, provided the spangles or ornaments be held between two crossing portions of upper thread and two aligned crossing portions of under thread, which upper and under threads are interlocked at the fabric at each 90 edge of the seam and also at or through the openings of the spangles or ornaments, substantially as above described.

I claim as my invention—

1. An embroidery-seam comprising fabric, 95 two crossing upper threads and two aligned crossing under threads fastened to the fabric at opposite edges of the seam, and spangles or analogous ornaments sustained flatwise in planes between the upper and under threads 100 and intermediately of the width of the seam, the thread portions lying at one face of each spangle being looped through the openings of the spangles and interlocked thereat by pas-

sage through said loops of the other thread portions lying at the opposite faces of the spangles or ornaments, substantially as described.

- 5 2. An embroidery-seam comprising fabric, two crossing needle-threads and two alined crossing shuttle-threads ranging in zigzag course along the seam, and spangles or analogous ornaments sustained flatwise by said
10 threads intermediately of the width of the seam and between two crossing portions of needle-threads and two crossing portions of shuttle-threads; the needle-threads being first looped through the fabric at one edge of the
15 seam and thereat interlocked by the shuttle-threads, said needle-threads being then looped through the spangle-openings and thereat interlocked by the shuttle-threads, said needle-threads then being looped through the fabric
20 at the other edge of the seam and thereat interlocked by the shuttle-threads; said threads thence passing diagonally again to the spangle-openings and interlocking therat and passing thence to and interlocking at the first piece of fabric, and so on along the seam, substantially as described.

- 25 3. An ornamental open-work embroidery-

seam comprising two separated and substantially parallel pieces of fabric, two crossing needle-threads and two alined crossing shuttle-threads ranging in zigzag course along the seam, and spangles or analogous ornaments sustained flatwise by said threads intermediately of the width of the seam and between two crossing portions of needle-threads and 30 two crossing portions of shuttle-threads; the needle-threads being first looped through one piece of fabric near its edge and thereat interlocked by the shuttle-threads, said needle-threads being then looped through the spangle-openings and thereat interlocked by the shuttle-threads, said needle-threads then being looped through the other piece of fabric near its edge and thereat interlocked by the shuttle-threads; said threads thence passing 40 diagonally again to the spangle-openings and interlocking therat and passing thence to and interlocking at the first piece of fabric, and so on along the seam, substantially as described.

CHARLES E. BENTLEY.
